VACUUM MACHINE

Neils P. Bach, Geneva, N. Y., assignor to American Can Company, New York, N. Y., a corporation of New Jersey

Application October 2, 1931, Serial No. 566,575

17 Claims. (Cl. 226—82)

The present invention relates to a machine or apparatus for vacuumizing and sealing containers and has for a particular object the provision of a rotating container carrier turret and a float valve engaging the turret and providing a seal for a vacuum chamber, the float valve utilizing atmospheric pressure for maintaining the proper fit, the amount of this holding pressure and its effect being carefully and accurately controlled at all times.

The present invention is particularly adapted to the use of a suction control device associated with a float valve of this general character, such a control insuring the proper sliding fit while preventing binding of the valve against the turret, all elements being self-contained and automatically compensating in their actions.

The principal object of the present invention is the provision of a control means for a float valve which operates so that the effect of atmospheric pressure against the valve during vacuumization of a container is partially counteracted and a definite controlled sealing pressure for the valve parts is maintained.

An important object of the present invention is the provision of a regulator for a float valve of the character described wherein the regulating device may be adjusted to provide any desired valve pressure for sealing a vacuum chamber.

A further important object of the invention is the provision of a pressure controlled float valve and a continuously rotating container carrier turret for conveying the containers into and out of a vacuum chamber, the vacuumized containers being closed in vacuum, the valve and turret controlled seal allowing a high degree of vacuum in the chamber while permitting easy operation of the turret.

Numerous other objects of the invention will be apparent as it is better understood from the following description, which, taken in connection with the accompanying drawings, discloses a preferred embodiment thereof.

Referring to the drawings:

Figure 1 is a sectional view taken through an apparatus for sealing containers in vacuum, this apparatus exemplifying a preferred embodiment of the present invention;

Fig. 2 is a longitudinal sectional view of the apparatus taken substantially along the broken line 2—2 in Fig. 1;

Fig. 3 is an enlarged sectional detail of one of the turret pockets with its enclosed sealing device for closing the container under vacuum; and

Fig. 4 is a fragmentary top plan detail of the turret section.

Such a preferred embodiment of the present invention comprises a combined vacuumizing and sealing apparatus mounted on a stationary frame which includes a unit base 21 on which is mounted a central column 22 and a side bracket 23. The column 22 provides a support for the container carrier turret and also carries a gear housing 24 mounted above.

The can carrier turret comprises a substantially cylindrical shell or turret member 25 provided with container pockets 26 adapted to receive containers 27 having a loosely applied closure or cover 28. A sealing mechanism is illustrated in the drawings for hermetically securing this cover 28 to its container.

The turret 25 is indirectly mounted for rotation on the column 22 and for this purpose is formed with a central sleeve 29 joined by a top plate 31 to its outer shell. The sleeve is formed with a bottom flange 32 which rests upon a ball bearing unit 33 carried by a flange 34 formed in the lower end of an inner sleeve 35 mounted for rotation on the column 22. The sleeve 35 is supported upon a ball bearing unit 36 which is carried upon a shoulder 37 formed in an intermediate web 38 of the column 22. In this way the column directly supports the sleeve 35 and the latter supports the turret, the bearing units allowing free and independent movement between column 22 and sleeve 35 and between the sleeves 35, 29.

The containers 27 are introduced into the machine in any suitable manner as by a conveyor chain 41 (Fig. 1) operating over sprockets 42 carried on a shaft 43 journaled in an extension table 44. This table may be carried by or otherwise properly associated with the frame of the machine so that the containers are delivered into the turret pockets. In such delivery they are guided between guide rails 45 and as each container approaches the inner ends of the rails, it is engaged by an arm of a rotating starwheel 46. This starwheel is mounted upon a vertical shaft 47 suitably journaled within the table 44 and is rotated in proper time with the travel of the chains 41.

Turret 25 is also rotated in synchronism with the starwheel 46 so that the engaged container 27 as it moves along the inner ends of the guide rails 45 is pushed by the starwheel into a pocket 26. Following this receipt of a container, the turret thereafter conveys it along a circular path of travel and against a forward extension 49 of one

of the guide rails. This forces the container fully within the pocket.

Rollers 51 are rotatably carried on the starwheel 46, there being one roller for each arm. A 5 roller 51 moving in its circular path of travel after the container has been discharged from the associated arm of the starwheel, comes into engagement with a circular cam wall 52 formed in one end of a rock lever 53. This lever is 10 mounted for oscillation upon a bolt 54 secured to the table 44. The opposite end of the lever 53 terminates in an inwardly extending finger 55 which engages the inserted container 27 carried inside of the turret pocket and pushes it inwardly 15 into fully seated position. This action is effected by oscillation of the lever 53 which is moved on its pivot when the roller 51 (Fig. 1) rides along the cam wall 52.

After the roller passes the lever, the latter is 20 moved back into normal position (shown in dotted lines Fig. 1) by a spring device. For this purpose the lever carries a sliding pin 56 which is pivotally secured at 57 adjacent the wall 52. A spring 58 is interposed between the lever and 25 a lug 59 mounted upon the table 44 and this tends to move the lever counter-clockwise on its pivot but yields under the rocking influence of the starwheel as just described.

The pockets 26 of the container turret 25 (Figs. 30 1 and 2) are spaced around its periphery and are less in height than the turret which leaves a solid or unbroken upper peripheral surface 65 above the pockets and a similar unbroken lower surface 66 below. These cylindrical walls, together with the intermediate cylindrical wall sections between pockets provide the proper movable surface for fit engagement with a float valve which is used to maintain a surrounding airtight seal for the pockets while they are successively under vacuum.

A float valve for this purpose comprises a semi-circular valve member 71 which is coextensive in height with the height of the turret 25 and which partially encircles the turret, extending and enclosing practically half of its cylindrical surface. This valve 71 is mounted for sliding movement within a housing 72 formed in the side bracket 23 of the frame and rests upon a bottom wall 73.

Extensions 75, project rearwardly from the 50 valve 71 and slide on exterior machined surfaces 76 of the housing 72. There is an extension 75 on each side of the housing and this valve mounting holds the float valve in proper aligned position relative to the turret 25.

55 Lugs 77 project laterally from each side of the housing 72, there being a lug in alignment with and to the rear of each extension 75. Each extension 75 carries a pin 78 which has sliding movement within its associated lug 77 and each 60 pin carries a spring 79 which is interposed between a lug 77 and an associated extension 75. These springs tend to force the float valve into engagement with the rotating turret 25 and assist, with other devices hereinafter described, 65 in producing the proper seal for the vacuum chamber.

The turret 25 is continuously rotated by connection with a source of driving power and for 70 this purpose a ring gear 81 (Fig. 2) is mounted on the flange 32 of the turret sleeve 29, this gear being just outside of the bearing unit 33. Gear 81 is engaged by a gear 82 carried on the upper end of a vertically disposed shaft 83 journaled in 75 a bearing 84 formed in the enlarged web section

38 of the column 22 and in bearings 86 formed in foot sections 87 of the column.

The shaft 83 also carries a gear 91 which meshes with a gear 92 keyed to the lower end of a vertically extending shaft 93 journaled in bearings 94 formed in the column. The upper end of shaft 93 extends into the gear housing 24 and carries a bevel gear 95 which meshes with a gear 96 mounted on a drive shaft 97 journaled in a bearing 98 formed in the housing 24. Shaft 97 also carries 10 a drive pulley 99 by means of which rotating power may be applied to the drive shaft. Collars 100 are pinned on the two ends of the shaft 93 and hold it in proper vertical position.

The inner face of the float valve 71 is recessed 15 at 101 (Figs. 1 and 3) and the pockets 26 of the turret which are adjacent said valve are simultaneously vacuumized to effect vacuum chambers for the sealing operation. This recess 101 provides air intercommunication and exhaust for 20 this purpose. A pipe 102 is threaded secured into the circular extension wall of the float valve and its opposite end is secured to a flexible connection 103 connecting with a pipe 104 threaded in a T 105, one arm of which is connected with a pipe 106 leading to a vacuum pump (not shown) or other suitable source of vacuum. By means of this connection air is withdrawn from the interior of those pockets 26 included between the engaged surfaces of the float valve and the peripheral walls of the turret. A vacuum chamber 30 is thus established which includes the pockets.

As long as this vacuum condition exists in the vacuum chamber atmospheric pressure on the exterior of the float valve 71 tends to force it 35 against the peripheral walls of the turret, the amount of this pressure varying with the degree of vacuum. In the present invention this circumstance is utilized in a unique manner by combining a device with the float valve which is 40 adapted to be more or less vacuumized so that it partially counteracts the atmospheric pressure on the valve and lessens the contact pressure of the valve against the turret.

The compensating function of such a device is 45 effective upon a substantial area of the rear exterior wall of the float valve and atmospheric pressure at this zone is replaced by a vacuum or rarefied atmosphere. A bellows 111 (Figs. 1 and 2) is located in the housing 72 and one end is 50 connected to the end wall of the housing while the opposite end connects with the flat outer or rear wall of the float valve. The interior of the bellows 111 is connected by a pipe 112 with the T 105 of the vacuum pipe 106. Air is thus withdrawn from the interior of the bellows at the same time that the air is extracted from the vacuum chamber.

A regulator valve 113 is preferably interposed 60 within the vacuum line 112 and this valve maintains a constant difference in air pressure or vacuum between the bellows and the vacuum chamber. This difference is under control of the operator, a regulating nut 114 screwing against the end of a spring 115 being provided for adjustment 65 purposes.

While a container is still in its vacuumized 70 turret pocket, it is desirable to seal or close it by securing its cover permanently in place. Sealing instrumentalities are preferably associated 75 with each turret pocket for this purpose, there being illustrated in the drawings (Figs. 2 and 3) a form of sealing device capable of bending a part of the cover flange into sealing position beneath a shoulder of its container.

Each turret pocket 26 is provided with centering plate ridges 121 which constitute locating walls for holding the container in its proper position for sealing. A shelf 122 is also extended 5 across the turret pocket being formed integrally with the pocket wall. Its upper surface is in horizontal alignment with the top of the table 44 and presents a surface over which the container 27 is moved as it enters the turret pocket.

10 A plunger device is located within the lower part of each pocket 26 and comprises a base plate 123 having a stem 124 slidably disposed within a bearing sleeve 125 carried in the turret 25. The upper surface of the base plate is also in the same 15 horizontal plane with the shelf 122 during insertion of the container within its pocket. The base plate provides the support for the container after it is seated in the members 121. When the rotating turret brings its pocket and container 20 to a position where it becomes a part of the vacuum chamber, the base plate is raised and the container is lifted into sealing position. This is effected in the following manner.

Each stem 124 at its lower end carries a roller 25 126 which rides upon a cam track 127 formed in the web 38 of the column 22. A pin 128 projects laterally from the stem 124 and cooperates with the track roller 126 by engagement with an annular cam track 129, also formed in the web 38.

30 The container 27 with its superimposed cover 28 is lifted through a partition 135 projecting inwardly from the pocket wall and cutting off a section of the upper part of the pocket for the cover sealing devices in a sealing head. The 35 cover in its raised position engages and is clamped on a chuck 136 located within the sealing chamber the plunger 123 providing the opposing clamping element for holding the container in sealing position.

40 The chuck 136 is carried on the lower end of a sleeve 137 which extends vertically through an outer sleeve 138 rotatably mounted in a bearing 139 formed in the turret. The plunger head 123 lifts the container first so that its cover engages 45 the chuck after which further lifting continues, this time accompanied by a lifting of the chuck with certain sealing devices carried thereby. This action is for a purpose hereinafter fully described.

50 Sealing of the container in vacuum and the accompanying bending of the cover flange under the container shoulder is effected by a floating die ring carried by and having horizontal movement on the chuck. This die ring (Fig. 3) comprises a collar 140 formed with a lower annular 55 ledge or bending jaw 141 and an upper annular ledge or supporting web 142 which engages with and is held by a flange 143 formed on the chuck 136. A cover plate 144 secured to the chuck by 60 screws 145 holds the die ring on the chuck in proper sliding position.

The jaw section 141 is cut away or tapered on its bottom corner edge to provide a tapered throat 146 through which the cover 28 and the upper 65 end of the container 27 move as the former is seated within the chuck. At this time the encircling walls of the throat 146 of the floating die ring are centrally disposed relative to the container and the cover and allow their free 70 passage through the throat. The necessary sliding movement imparted to the floating die ring 140 to effect the proper bending action is controlled by an eccentrically mounted collar member 151 which is loosely mounted on an eccentric 75 section 152 formed in the lower end of the sleeve

138. Collar 151 has no vertical movement being held in vertical position by a locknut 153 threadedly secured to the end of the sleeve 138, this construction permitting rotation of the sleeve within the collar. 5

Rotation of the sleeve 138 and the eccentric, shifting movement of the collar 151 imparts a similar shifting to the floating die member 140. This relative movement between collar and chuck may be described as horizontal and is utilized as 10 a driving means for the floating bending die. The collar 151 is formed with an annular wall 154 having a bottom inner edge tapered at 155.

At the time the floating die member 140 is 15 lifted with the chuck 136 in the second stage of insertion of the container into the sealing chamber as described, an upper and outer tapered wall 156 formed in the die ring engages and seats within the tapered wall 155 of the collar 151. When in this locked position the die ring 140 20 moves in unison with the shifting collar and also describes a horizontal motion. This movement forces one side of the jaw 141 against the lower skirt of the cover 28 and bends it under a shoulder on the container as illustrated on the left-hand side in Fig. 3. As the movement continues, adjacent sections of the jaw 141 progressively 25 engage the depending skirt of the cover flange and complete the bending thereof in one complete rotation of the sleeve 138. 30

The sleeve 138 is rotated by a connection best illustrated in Fig. 2. For this purpose the sleeve 138 is formed at its upper end with an enlarged gear section 161, the teeth of which engage a central gear 162 keyed to the upper end of the sleeve 35. This sleeve 35 and the gear 162 are rotated on the column 22 by a gear train which comprises a gear section 163 formed in the lower end of the sleeve which meshes with a gear 166 (see also Fig. 1) which rotates upon a stud 167 40 supported by the column web 38. The gear 166 is integral with a superimposed gear 168 which meshes with a gear 169 formed as a lower gear section of the gear 82. 45

To assist in a controlled raising and lowering 50 of the chuck 136 and the sleeve 137 when the container is lifted by the base plate 123, a cam track is used for cooperation with the cam truck 127. The upper end of each sleeve 137 carries a cam roller 175 which traverses a peripheral cam track 176 formed in a stationary cam disc 177 keyed to the column 22 and located directly above the gear 162. A locking collar 178 threadedly engages the column and rigidly clamps the cam disc. 55

The contour of the cam track 176 corresponds in part with the cam track 127 so that after a container 27 is clamped between the base plate 123 and the chuck 136, all of these parts will raise together and the floating die ring 140 locks 60 with its actuating collar 151. The cam track 176 also cooperates with the cam 127 to simultaneously lower the chuck, container and base plate after sealing. 65

Lowering of the die ring 140 disengages its 70 tapered wall 156 from the tapered wall 155 of the collar 151 and following this a tapered wall 181 formed in the outside lower corner edge of the die ring engages a similar tapered surface 182 formed in the partition 135. Centralizing of the die ring 75 takes place as it shifts over with its wall into full engagement with the wall surrounding the opening in the partition. The inwardly projecting jaw section 141 is now in a central position and free of the container and its sealed cover and 75

continued lowering of the base plate 123 again brings the sealed container into its lowered position in the turret pocket.

To insure positive discharge from the sealing head this lowering action is accompanied by a positive stripping of the sealed container from the chuck. For this purpose a knockout pad 185 (Figs. 2 and 3) is used being normally located within a pocket 186 in the chuck 136. It is secured to the lower end of a knockout rod 187 which is slidably disposed within the sleeve 137. The upper end of the rod 187 carries a cam block 188 (see also Fig. 4) which rides against the outer wall of a cam 189 mounted upon the cam disc 177. The block 188 carries a cam roller 191 which operates within a cam groove 192 formed in the cam 189.

When the chuck 136 has reached its lowered position, the knockout pad 185 with its rod 187 continues downwardly with the lowering of the base plate 123 and resting on the sealed container, positively discharges it from the chuck.

The sealed container 27 still on its lowered base plate 123 further is carried into a position of discharge. The pocket 26 containing the container moves beyond the end of the float valve 71 and atmospheric air enters the pocket. A container finger discharge located within each pocket (Fig. 1) now comes into play to eject the container from the pocket. Each device comprises a pair of swinging arms 195 located one above and one below the top and bottom guide ridges 121 and normally out of contact with the container. These two arms are secured to a vertically disposed shaft 196 which extends through the turret wall.

An arm 197 (Figs. 2 and 4) is secured to the upper end of each shaft 196 and carries a roller 198 which operates within a cam groove 199 formed in the lower face of a collar cam 201 mounted on the cam 189. Bolts 202 are threadedly engaged within the cam disc 177 and pass through the cam members 189, 201 locking these cam parts in stationary position.

The cam 201 effects oscillation of the arm 197 and the shaft 196 which controls movement of the fingers 195 so that the sealed container 27 when carried to a position of discharge is moved out of its turret pocket (Fig. 1). A guide rail 205 is disposed adjacent the turret and prevents premature discharge of a sealed container from its turret pocket, this guide rail being a part of one of a pair of spaced rails 206 formed in a discharge table 207. The fingers 195 move the sealed container onto the table 207 where it is engaged by a pair of moving discharge chains 208 passing over sprockets 209 mounted on a shaft 211, journaled in the table.

Unsealed containers are thus fed in succession into adjacent turret pockets and after sealing in vacuum the containers are successively discharged each pocket emptying its sealed container as it passes adjacent the position of discharge.

It is thought that the invention and many of its attendant advantages will be understood from the foregoing description, and it will be apparent that various changes may be made in the form, construction and arrangement of the parts, without departing from the spirit and scope of the invention, or sacrificing all of its material advantages, the form hereinbefore described being merely a preferred embodiment thereof.

I claim:

1. In an apparatus for vacuumizing contain-

ers, the combination of a stationary frame, a container carrying turret rotatably mounted in said frame, a float valve interposed between said frame and said turret on which valve the turret has sliding contact so that the valve forms a sliding seal for a vacuum chamber, and vacuum means associated with said float valve for partially counteracting the effect of atmospheric pressure against it when said chamber is under vacuum.

2. In an apparatus for vacuumizing containers, the combination of a stationary frame, a container carrying turret rotatably mounted in said frame, a float valve interposed between said frame and said turret and on which said turret has sliding contact forming a sliding seal for a vacuum chamber, means associated with said float valve for partially counteracting the effect of atmospheric pressure against it when said chamber is under vacuum, and means for regulating said counteracting means in accordance with the amount of vacuum in said chamber.

3. In an apparatus for vacuumizing containers, the combination of a stationary frame, a container carrying turret rotatably mounted in said frame, a float valve interposed between said frame and said turret and forming a sliding seal for a vacuum chamber with which valve the turret has sliding contact, vacuum means associated with said float valve for partially counteracting the effect of atmospheric pressure against it when said chamber is under vacuum, and means for adjusting said counteracting means.

4. In an apparatus for vacuumizing containers, the combination of a stationary frame, a container carrying turret rotatably mounted in said frame, a float valve interposed between said frame and said turret and forming a sliding seal for a vacuum chamber, and a bellows connected with said float valve and with a source of vacuum for partially compensating the pressure of the outside atmosphere against the valve while said chamber is under vacuum.

5. In an apparatus for vacuumizing containers, the combination of a stationary frame, a container carrying turret rotatably mounted in said frame, a float valve interposed between said frame and said turret and forming a sliding seal for a vacuum chamber, a bellows connected with said float valve and with a source of vacuum for partially compensating the pressure of the outside atmosphere against the valve while said chamber is under vacuum, and means for regulating the amount of vacuum within said bellows.

6. In an apparatus for vacuumizing containers, the combination of a stationary frame, a container carrying turret rotatably mounted in said frame, a float valve interposed between said frame and said turret, yielding devices for forcing said float valve into contact with said turret to provide a sliding seal for a vacuum chamber, and vacuum means associated with said float valve for partially counteracting the effect of said yielding devices and atmospheric pressure against it when said chamber is under vacuum.

7. In an apparatus for vacuumizing and sealing containers, the combination of a stationary frame, a container carrying turret having a plurality of container receiving pockets rotatably mounted in said frame, a float valve interposed between said frame and said turret, means for forming a vacuum in said turret pockets, container sealing instrumentalities carried by said turret for sealing said containers while in said vacuum, and a vacuum conduit including a mov-

able member secured at its opposite ends to said frame and valve respectively for partially counteracting the effect of atmospheric pressure against said valve during such vacuumizing and sealing.

8. In an apparatus for vacuumizing and sealing containers, the combination of a stationary frame, a container carrying turret having a plurality of container receiving pockets rotatably mounted in said frame, container sealing instrumentalities located in each pocket, a float valve interposed between said frame and said turret, means for forming a vacuum in said turret pockets, actuating means for causing said instrumentalities to seal a container when its pocket is vacuumized, and a vacuum conduit including a movable member secured at its opposite ends to said frame and valve respectively for partially counteracting the effect of atmospheric pressure against said valve during such vacuumizing and sealing.

9. In an apparatus for vacuumizing containers, the combination of a stationary frame, a container carrying turret rotatably mounted in said frame, a float valve interposed between said frame and said turret and forming a sliding seal for a vacuum chamber, vacuum means associated with said float valve for partially counteracting atmospheric pressure against it when said chamber is under vacuum, and means for adjusting said counteracting means in accordance with the vacuum in said chamber to effect a predetermined pressure contact between said floating valve and said turret.

10. In an apparatus for vacuumizing containers, the combination of a bodily fixed part and a relatively movable part contacting with each other and defining a vacuum chamber adapted to receive a container to be vacuumized, means for vacuumizing said chamber, and means responsive to said vacuumizing means for lessening pressure contact between said fixed and movable parts created by the vacuum in said chamber.

11. In an apparatus for vacuumizing containers, the combination of a rotary turret having means to receive and close a container, a fixed part, and a valve having a sliding contact with said fixed part and engaging said turret to form a vacuum chamber to enclose the container, and vacuumizing means operating on said valve to lessen the friction between said turret and valve and also operating to vacuumize said chamber.

12. In an apparatus for vacuumizing containers, the combination of a rotary part having chambers, a non-rotary part arranged to leave open and to close said chambers as said rotary part turns, vacuum means for relieving the mutual friction of said parts, means for vacuumizing said chambers when closed, means for mov-

ing the containers vertically in said chambers when the chambers are closed, and means for closing the containers when they are in vacuumized condition.

13. In an apparatus for vacuumizing containers, the combination of a rotary part having chambers, a non-rotary part arranged to leave open and to close said chambers as said rotary part turns, means for vacuumizing said chambers and containers therein when the chambers are closed, means for closing the containers when they are in vacuumized condition, and a vacuumized device operating on said non-rotary part for lessening the contact pressure between said rotary and non-rotary parts.

14. In an apparatus for vacuumizing containers, the combination of a rotary turret, a float valve engaging the turret to form a vacuum chamber, means for vacuumizing said chamber whereby said turret and valve are frictionally urged together due to external atmospheric pressure opposing the vacuum, and means for applying the vacuum to press said valve in the contrary direction, whereby the friction between the turret and valve is reduced.

15. In an apparatus for vacuumizing containers, the combination of a part, a turret defining a vacuum chamber in conjunction with said part, said chamber adapted to contain a container, and vacuum means for controlling pressure contact between said part and turret created by the vacuum in said chamber, said means comprising devices producing a counter vacuum, in partial relief of the pressure created by the vacuum in said chamber.

16. In an apparatus for vacuumizing containers, the combination of a container conveyor, a valve casing contacting said conveyor and substantially sealing it against the atmosphere, a vacuum chamber formed in part by said conveyor and having container sealing mechanism therein, vacuum means for exhausting the air from said chamber and simultaneously from a plurality of containers therein, said vacuum means causing relative movement between said conveyor and said casing, and auxiliary means responsive to said vacuum means for controlling said movement.

17. In an apparatus for vacuumizing and sealing containers, the combination of a container conveyor, a valve casing adapted to seal said conveyor against the atmosphere, a vacuum chamber formed in part by said conveyor and containing mechanism for sealing a container, a vacuum means for exhausting the air from said chamber and container and causing relative pressure between said conveyor and said casing, and counter vacuum means for controlling said pressure.

NEILS P. BACH. 60
